UNITED STATES PATENT OFFICE

2,609,714

POWER TOOL FEED DEVICE

Theodore E. Mead, Wilmette, Ill.

Application October 4, 1947, Serial No. 777,991

3 Claims. (Cl. 77—33.5)

1

This invention relates to a power tool feed device. The invention is particularly useful in feeding longitudinally a power tool, such as a drill press which is being rotated as it is advanced. It will be understood that the invention is applicable to many other uses.

For the purpose of simplicity of illustration, the invention herein will be described in connection with the feeding of a drill press.

An object of the invention is to provide a simple structure for feeding, in a longitudinal direction, a rotary tool, such as, for example, a drill. A further object is to provide mechanism which may be readily attached to the quill of a drill press or to other longitudinally movable portions of a power tool for moving the tool longitudinally in the feed operation. Yet, another object is to provide a power cylinder structure equipped with a clamp means for ready attachment of the cylinder to a longitudinally movable tool, while providing means for accurately controlling the feed of the tool toward the work. Other specific objects and advantages will appear as the specification proceeds.

The invention is illustrated, in a single embodiment, by the accompanying drawing, in which—

Figure 1 is a broken side view in elevation of apparatus embodying my invention and illustrated as applied to a drill press; Fig. 2, a view similar to Fig. 1 but showing the quill of the drill press advanced to a lower position by the feed mechanism; and Fig. 3, a broken longitudinal sectional view of the valve structure which may be employed.

In the illustration given, 10 designates a drill press of usual and well-known construction. The press is provided with the usual shoulder or arm 11, which extends outwardly from a supporting standard and in which is guided the movable quill 12. The longitudinally movable quill 12 is provided with a yoke 13, and below the yoke is an adapter 14 receiving the drill bit 15.

In the embodiment of the invention illustrated, I provide a power cylinder casing 16 equipped with a head 17 providing a guide boss 18 for the piston stem 19. The piston stem 19 is connected at its inner end to the usual piston 20.

The head 17 is unusual in contour, in that it is provided with a lateral extension 21 recessed to receive the quill 12. The outer end of the recessed extension 21 is closed by a removable clamp 22. Bolts 23 extend through each end of the clamp 22 to engage the U-shaped side walls of the extension 21 and to close such side walls about the quill 12.

2

The bottom of the cylinder is tapped to receive the threaded end 24 of a needle valve 25. The needle valve 25 is provided with a valve chamber 26, which communicates through a valve seat 27 with a flow passage 28 leading into the cylinder 16. The valve casing is provided with a laterally-extending intake fitting 29, which is carried by means of a flexible conduit 30 to the usual valve which provides for an exhausting of the pressure fluid and for the inlet of pressure fluid, the valve being connected to a suitable source of pressure fluid. A suitable valve for the control of the exhausting of pressure fluid from the cylinder 16 and for the establishing of communication between a source of pressure fluid and cylinder 16 is that shown in my co-pending application, Serial No. 614,414, for Valve Structure, now Patent No. 2,505,333, issued April 25 1950.

The needle valve 25 may be of any suitable form or construction. In the illustration given in Fig. 3, the valve casing provides a rearwardly-extending threaded passage 31 adapted to threaded receive a shaft 32. The shaft 32 is provided with a recess 33 at its forward end and has an inwardly-extending flanged end 34. A conical valve 35 is aligned with valve seat 27 and is provided with a rearwardly-extending shaft 36. The inner end of the shaft is enlarged or provided with a shoulder 37 for engagement with the flanged end 34 of shaft 32. A packing nut 38 may be employed to secure packing 39 about the end of the valve casing. A knurled knob 39 is illustrated as fixed to the shaft 32 by the set screw 40.

Instead of the valve illustrated in Fig. 3, a valve, such as is shown in my co-pending application, Serial No. 777,992, for Needle Valve Structure, may be employed.

Operation

In the operation of the device, compressed air or other pressure fluid is admitted through a suitable control valve to the inlet conduit 29 of the needle valve. The fluid flows through the valve chamber, valve seat and into the lower portion of the power cylinder chamber. Since the piston shaft or stem 19 engages the fixed shoulder or arm 11 of the drill press, the piston is not free to move upwardly but is held in a fixed position. The casing 16, however, since it is secured to the movable quill, may move, and as a result, the cylinder casing 16 moves slowly downwardly to a lower position, as indicated in Fig. 2. In such feeding operation, it is found that air pressure is extremely effective in producing a feeding of the

tool with the desired pressure and at the desired speed.

The usual spring structure used within the drill press casing 10 retracts the quill 12 upon the exhausting of the power fluid from the cylinder 16. When the pressure fluid fed to the valve chamber 26 is cut off and the exhaust port opened, as in the usual operation, the pressure fluid flows back from the cylinder 16 through the valve seat 27 and outwardly through the fitting 29. In this operation, the exhaust is speeded up because the valve 35 is free to move rearwardly a limited distance. On the other hand, when pressure fluid is again fed into the valve chamber 26, the fluid carries the valve 25 forwardly to its controlling position with respect to valve seat 27 for the power operation.

The cylinder casing may be attached to the drill press and to other power tools without requiring any change at all in the power tool. The head 17 may be secured to the quill or tube of the tool by inserting the same around the tool, and the clamp end 22 may then be secured in position. In the tool press structure, the U-shaped arms of the extension 21 may be secured upon the quill above yoke 13 or they may rest upon the yoke 13 of the quill and exert downward pressure thereon. In the latter arrangement, the flat extension 21 bearing against the flat yoke 13 supports the cylinder 21 squarely in position during the downward feeding of the member 12. The recess of extension 21 snugly receives the quill and when the clamp end 22 is screwed into position it secures the extension tightly to the quill.

The power cylinder structure and attachment therefor, which has been described in connection with a power drill press, may obviously be used with very slight modifications for actuating the movable portion of other tools of many types.

The threaded rod 41 slidably supported in the boss 42 is equipped at its top with two lock nuts 43 and 44 which provide a depth-stop and support a snubber spring 45. The snubber spring is short and stiff and will slow down the movement of the drill by absorbing power exerted by the cylinder. Thus, by adjusting the two lock nuts on the threaded rod provided as a depth-stop, the drill feed will be decelerated as it breaks through the bottom of a piece of work, thus preventing "snagging" and injury to the drill. The snubber spring serves an important new purpose when employed in connection with the apparatus and with the compressed air feed structure.

While in the foregoing specification I have set forth a single structure in great detail for the purpose of illustrating my invention, it will be understood that the details of such structure may be varied widely by those skilled in the art without departing from the spirit of my invention.

I claim:

1. A feed device for a longitudinally-movable tool supported in a fixed frame, said longitudinally-movable tool being guided by a stationary

arm and being equipped near its lower end with a yoke, an air cylinder provided at one end with an air inlet and at the other end with a head having a central passage therethrough, a piston in said cylinder provided with a stem extending through said head passage and having a tip freely engaging said stationary arm, said head being provided with laterally-extending arms resting upon said yoke and secured about said longitudinally-movable tool, and means for supplying compressed air to said inlet of said cylinder.

2. A feed device for the longitudinally-movable quill of a rotary drill press, said press being provided with a stationary arm for supporting the longitudinally-movable quill and said quill being provided near its lower end with a yoke, an air cylinder closed at its bottom and provided with an air inlet, means for supplying compressed air to said inlet, a piston slidably mounted in said cylinder, a long piston stem secured to said piston having a pointed outer end, and a head provided with a guide passage therein for receiving said piston stem to direct said outer end freely against the stationary arm of said press, said head being provided with a pair of laterally-extending and spaced-apart arms resting upon and engaging said yoke whereby upon the upward movement of said piston stem bearing against said stationary arm, said yoke and quill are caused to move downwardly.

3. A feed device for a longitudinally-movable tool supported in a fixed frame, said longitudinally-movable tool being guided for vertical movement in a stationary horizontal supporting arm of the frame, said longitudinally-movable tool being provided with a yoke providing horizontal shoulders, a cylinder closed at its bottom and provided at its bottom with an air inlet, means for supplying compressed air to said inlet and for exhausting said air therefrom, and a head closing the top of said cylinder and provided with a guide boss having a passage therethrough, said head being provided with a pair of laterally-extending integral arms resting upon the shoulders of said yoke and on either side of said longitudinally-movable tool, a piston slidably mounted in said cylinder provided with a stem extending through said guide boss and having a rounded tip freely engaging an under surface of said supporting arm.
